UNITED STATES PATENT OFFICE

ROBERT K. JAMISON, OF KANSAS CITY, MISSOURI

DESIGN FOR A SIGNAL PLAQUE

Application filed January 20, 1933. Serial No. 46,897. Term of patent 8½ years.

To all whom it may concern:

Be it known that I, ROBERT K. JAMISON, a citizen of the United States, residing at Kansas City, Jackson County, Missouri, have invented a new, original, and ornamental Design for Signal Plaque, of which the following is a specification, reference being had to the accompanying drawing, forming a part thereof.

In the drawing:—

Figure 1 represents a face view of a signal plaque showing my new design.

Figure 2 represents a side elevation of a signal plaque showing my new design.

Figure 3 represents a central vertical section through a signal plaque showing my new design shown in Figure 1.

Figure 4 is a top plan view of a signal plaque showing my new design.

Figure 5 is a bottom plan view of a signal plaque showing my new design.

I claim:—

The ornamental design for a signal plaque as shown.

ROBERT K. JAMISON.
